UNITED STATES PATENT OFFICE.

RICHARD D. MARTIN, OF FORT SMITH, ARKANSAS.

COKE-DRAWING MACHINE.

Application filed December 13, 1921. Serial No. 522,087.

To all whom it may concern:

Be it known that I, RICHARD D. MARTIN, a citizen of the United States, and a resident of Fort Smith, in the county of Sebastian and State of Arkansas, have invented a new and Improved Coke-Drawing Machine, of which the following is a description.

My invention relates more particularly to a machine for taking coke out of beehive ovens and has for its general object to provide a machine highly efficient for its purpose and so compact as to allow sufficient space on a standard width coke oven dock or wharf to permit the piling of the coke 10 between the machine and the railroad track for loading.

Important objects also are to provide a scraper beam so mounted as to have the maximum movements into and out of the 20 oven but in keeping with the aim of compactness; and to provide for lateral turning movement of the beam as well as for vertical tilting movement as may be required.

A more specific object of the invention is 25 to provide a machine for the stated purpose improved in various particulars with a view to promote convenience of assemblage, operation and control, as well as to provide a construction in which the different moving 30 parts are properly guided and braced and the machine thus made durable.

The above and other objects as will appear are attained by a coke drawing machine mounted on a truck traveling on a 35 track with the oven walls at one side, there being space for the coke pile on the opposite side of the track, my improved assemblage permitting of the travel of the machine on the track in a more limited space than is 40 possible with machines of ordinary construction.

The nature of the invention and its distinctive features and characteristics will clearly appear as the description proceeds.

Reference is to be had to the accompanying drawings, it being understood that the drawings are merely illustrative of one example of the invention.

Figure 1 is an elevation of a coke-drawing

machine embodying my invention, illustrating the scraper beam entered to the full extent into a coke oven shown in vertical section;

Figure 2 is a plan view of the machine with the oven in horizontal section;

Figure 3 is a longitudinal vertical section as indicated by the line 3—3, Figure 4;

Figure 4 is a transverse vertical section on the line 4—4, Figure 3;

Figure 5 is a plan view with the scraper 60 beam in the rearward position and swung at an angle to the medial line position of Figure 2.

Figure 6 is a sectional view taken on line 65 6—6 of Figure 3.

In carrying out my invention in accordance with the illustrated example track rails 10 are laid in front of the coke oven A. The wheels 11 of a truck designated generally by the numeral 12 run on the rails 10. 70 The truck 12 has a transverse track 13, the rails of which are of channel form. Running in the channel rails of the track 13 are wheels 14 on the axles 15 of a carriage designated generally by the numeral 16 and having a platform 17. To the platform 17 a platform 18 is swivelled by a king bolt 19, said platform 18 being above platform 17 as clearly shown in Figures 3 and 4. On the platform 18 is a frame presenting spaced 80 sides 20 on which is mounted an elongated tubular guideway 21 by a slot and pin connection, there being slots 22 in the sides 20 and a pin 23 passing through said sides and through flanges 24 on said guideway 21. The 85 scraper beam 25 having a scraper head 26 is adapted to telescope in the guideway 21, said guideway having steady rollers 121 at the interior, the sides 27 of said scraper beam being of channel form to engage said 90 rollers 121. To move the scraper beam 25 longitudinally into or out of the guideway 21, I provide a screw 28 in the guideway 21, the rear end of the screw being held to a block 29 in said guideway, the screw having parallel flanges 30 and the block 29 having corresponding annular grooves 31 so that the screw has a swivelled connection

with the guideway at the said rear end. The screw is plain or has the threads turned off as at 32, 33, the screw at its front end extending through an internally threaded block 34 on the rear end of the scraper beam 25, there being a collar 35 on the screw at the front end against which the block 34 may come to a bearing in the extreme outward movement of the scraper beam 25. The plain or unthreaded terminals 32, 33 of the screw 28 are for the purpose of disengaging the threads of said screw from the threaded traveller block 34 of the scraper beam 25 at the extremities of both the forward and rearward movements of the scraper beam 25, whereby to limit the action of the screw 28 in actuating the beam 25 and disengage the latter to prevent over-winding after the scraper bar has reached the limit of a forward or rearward movement. Suitable means is provided for driving the screw 28, there being conventionally indicated in the drawing a motor 36, the shaft 37 of which has in the illustrated example a bevelled pinion 37^a in mesh with a similar pinion 38 on the rear end of said screw. It is to be observed that the motor 36 for driving the screw 28 is mounted on the guideway 21 or at all events is rigid with the guideway 30 and with the platform 18 to preserve a constant relation between the motor and said guideway and platform irrespective of the transverse movement of the platform 18 and carriage 16 on the truck 12 and irrespective 35 of the tilting of the guideway or the telescoping movements of the scraper beam 25.

With the above described arrangement the carriage 16 may be moved transversely of the truck and rails 10 by reason of the wheels 40 14 traveling in the channel track rails 13 and in such transverse movement of the carriage 16 the guideway 21 and scraper beam 25 will be carried bodily by an axial movement thereof into or out of the coke oven, 45 according to the direction of travel of the carriage 16.

In addition, the telescoping beam 25 may be given longitudinal movement by the screw 28 to the desired extent into or out 50 of the guideway 21. Thus, it is to be noted that a longitudinal movement of the beam 25 into or out of the furnace is in part effected by the movement of the carriage 16 to carry with it said scraper beam and in 55 part by the movement of said scraper beam relatively to the guideway and carriage. For swinging the scraper beam 25 laterally in the coke oven, that is to say, for giving said scraper beam an angular position at 60 either side of the medial vertical plane of the coke oven, the platform 18 is turned with the king bolt 19 as an axis. Besides the turning movement on the king bolt 19 and the axial movement given the beam by the 65 transverse travel of carriage 16 and the tele-

scoping of said beam, the guide 21 and scraper beam 25 may be rocked vertically with the cross pin 23 as an axis. The slot and pin connection as at 22, 23 permits of the bodily rising of the guide 21 and scraper beam on the platform 18, if for any reason this should be found desirable. To hold the guide 21 in the tilted position suitable means is provided, the following means being employed for the purpose in the illustrated form. At one end of the platform 18 is an arch 39 having transverse holes 40 in two vertical series, the holes in the respective series being staggered. A pin 41 is adapted to pass through alined holes 40 in the opposite sides of the arch 39 and through a slot 42 in a block 43 on the top of the guideway 21.

When the scraper beam 25 and its guideway 21 are entirely withdrawn from the coke oven and clear of the front wall thereof, they may be turned through a complete circle about the king bolt 19. For turning the platform 18 and the mounted guideway 21 and scraper beam 25 about the king bolt 19 I provide an annular rack 44 rigid with the platform 17 and I provide a pinion 45 on a vertical post 46 partly mounted in the platform 18 and provided with a handwheel 47. By turning the hand wheel 47, post 46 and pinion 45, said pinion will be caused to walk or travel about the periphery of the rack 44 thereby turning the platform 18 and the super-structure thereon including the guide 21 and scraper beam 25. In the turning movement of the platform 18 I guide and brace the same by depending keepers 48 on the platform 18, the lower ends of the same being directed laterally inward as at 49 beneath the rack 44, said keepers being provided at diametrically opposite sides of the platform 18. The king bolt 19 extends through the platform 18, gear 44, and platform 17 and between hanger brackets 50 on the under side of the platform 17, said hangers having transverse holes therein to receive a transverse pin 51 which is passed through said hangers and through the king bolt 19 below the platform 17.

For giving transverse movement to the carriage 16, that is to say, for causing the wheels 14 of said carriage to travel in the channel rails 13, I provide racks 52 on bars 53 secured to the platform 17 at the under side, said bars 53 being disposed in pairs one pair at each side of the platform adjacent to the inner sides of the rail 13, the axle 15 having bearings in said bars 53. The racks 52 have their teeth at the under side as clearly shown in Figure 3 and they mesh with pinions 54 on a shaft 55 which is driven by a motor 56 through a suitable reducing gear train 57, said motor and gear train being mounted on the truck 12.

The positions of the pinions 54 on the truck 12 are such that the racks 52 will disengage themselves from the teeth of the driving pinions 54 at the limit of a movement of the carriage 16 in either direction on the truck 12 so that the drive pinions 54 may continue to turn after giving the maximum movement to the carriage and without affecting the carriage after the disengagement of the racks.

For propelling the truck 12 a bevel pinion 58 is keyed on the shaft 55 and meshes with a similar pinion 59 on one of the axles 60 of the truck. Thus, the machine is propelled on the track 10 and transverse movement given to the carriage 16 by a motor on the truck frame while the screw 28 for effecting the telescoping movement of the scraper beam 25 is driven by the motor (36) on the carriage.

The hub 61 of the pinion 59 is adapted to be shifted by a lever 62 to throw said pinion 59 into or out of gear with the drive pinion 58.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. In a coke-drawing machine, a truck adapted to travel on a track, a carriage mounted to travel on said truck, coke-drawing means mounted for longitudinal movement on said carriage, means for actuating said coke-drawing means, and propelling means for said carriage independent of said coke-drawing means and its actuating means to impart to said carriage movements in the same directions as the movements given the coke-drawing means by said actuating means.

2. In an apparatus of the class described, a wheeled truck, a guide on said truck, a support on which said guide is vertically tiltable, means turnably mounting said support for lateral movement and a scraper beam longitudinally movable in said guide.

3. In an apparatus of the class described, a scraper beam, a guide in which said beam telescopes, and a screw in said guide adapted to have threaded engagement with said beam, said screw being held against axial movement.

4. In an apparatus of the class described, a wheeled truck, a carriage movable transversely on the truck, a guide on said carriage disposed transversely of the truck, a scraper beam telescoping in said guide, a screw in said guide adapted to have threaded engagement with the scraper beam, and means to

hold said screw against axial movement, said screw having unthreaded terminals to cause disengagement of the beam at the extremity of each movement into or out of the guide.

5. An apparatus of the class described including a wheeled truck, a carriage having a platform turnably mounted on the truck, a second platform turnably mounted above the first platform, means to move said platforms in unison transversely of the truck, and means to turn the second platform independently of the first platform; together with a scraper beam supported on said second platform.

6. An apparatus of the class described including a wheeled truck, a carriage movable transversely on said truck, a guideway on said carriage, a screw in said guideway, a scraper beam movable longitudinally by said screw, and a motor mounted on said guideway and having driving engagement with said screw.

7. An apparatus of the class described including a wheeled truck, a carriage mounted to travel transversely on the truck, coke drawing means mounted on said carriage, a rack on the carriage, a pinion turnably mounted on the truck and engaging said rack, and means to drive said pinion, said rack being adapted to disengage itself from the pinion at the extremity of movement of the rack in either direction.

8. In a coke drawing apparatus, a scraper beam, means to support the same for movement into or out of the coke oven, a screw coaxial with the beam and adapted to have threaded engagement therewith for actuating the beam, and drive means for said screw.

9. In a coke drawing apparatus, a scraper beam, means to support the same for movement into or out of the coke oven, a screw coaxial with the beam and adapted to have threaded engagement therewith for actuating the beam, and drive means for said screw; together with means to limit the longitudinal movement of the scraper beam without stopping the screw.

10. In an apparatus of the class described, a wheeled truck, a carriage mounted on said truck for transverse movement thereon, a guide on said carriage transversely of the truck, a scraper beam movable axially in said guide, means mounting said guide for vertical tilting movement, an arch over said guide, and a transverse pin adapted to variously engage said arch for holding the guide in various vertical adjustments.

11. In an apparatus of the class described, a wheeled truck, a fixed platform thereon, a carriage mounted to travel transversely on said truck, a platform on said carriage, a king bolt securing the platform to the carriage, a fixed annular rack on the carriage, a pinion turnably mounted on the platform

- and engaging said rack, manually operable means for turning said pinion to cause turning movement of said platform, and coke scraping means mounted on said platform.
- 5 12. In an apparatus of the class described, a wheeled truck, a guide on said truck, a support for said guide, a slot and pin con-

nection between the support and guide to permit a vertical tilting of the guide with the pin as an axis, or a bodily vertical movement thereof to the extent of the slot, and a scraper beam longitudinally movable in said guide. 10

RICHARD D. MARTIN.
